JOHN RAIBLE, MATTHIAS REIS, AND JOHANN RITTER, OF CHICAGO,
ILLINOIS

Letters Patent No. 99,002, dated January 18, 1870.

IMPROVEMENT IN SELF-CLEANING FILTERS FOR HYDRANTS.

The Schedule referred to in these Letters Patent and making part of the same

To all whom it may concern:

Be it known that we, JOHN RAIBLE, MATTHIAS REIS, and JOHANN RITTER, of Chicago, in the county of Cook, and State of Illinois, have invented certain new and useful Improvements in Water-Filters; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention consists in a novel manner of constructing a filter, so as to be self-cleaning, the act of shutting off the feed-water also opening a valve, through which the accumulated sediment within the filter escapes.

In the drawings—

Figure 1 is a vertical section through our filter, on the line $z z$ of fig. 2;

Figure 2 is a top plan view of the filter;

Figure 3 is a side elevation of the same; and

Figure 4 is a horizontal section, taken on the line $y y$ of fig. 3, looking upward.

A is the filter-body, a globular vessel, made in two parts, bolted together, and having stretched across its interior the filtering-diaphragm a . This diaphragm consists of a sheet of felt, placed between two sheets of wire gauze, and it is held in place by having its edges held between the flanges of the two parts of body A, and through which the bolts are passed for holding said parts together. The body A we mount upon suitable legs or frame-work, so as to maintain the diaphragm in a horizontal position.

B is a pipe attached to the lower end of the body A, and through which the water is forced, under pressure, into the body and up through the diaphragm.

C is a stand-pipe, attached to the upper end of the body A, and through which the filtered water ascends, and is drawn off for use through a cock, b , provided for that purpose.

The pipe B we provide with a cock, d , for shutting off the supply of water, and this cock we provide with an operating-rod, e , having a handle, f , at its upper end, at a convenient height for grasping with the hand.

The rod e is supported by passing through the flanges of vessel A, and by an arm attached to the upper end of stand-pipe C, as shown in figs. 1 and 3.

At the lower end of the body A we form an opening, k , and over the outside of this opening locate a pivoted valve or gate, j , provided on its outer end with a segmental rack, as shown in fig. 4.

On the rod e we secure a pinion, i , meshing into the rack on valve j , so that as the rod e is turned so as to open valve d , and admit water to the body A, it will operate valve j and close the opening k , and as the valve d is again closed, the opening k will be opened.

To the outside of the body A, we attach a shelf, h , upon which to place vessels while being filled with water from the filter.

We also provide the body A with a cock, g , just above the diaphragm, for the purpose of drawing off any standing water above the diaphragm in winter, and thus prevent the apparatus from freezing up and becoming inoperative.

The operation of our device is as follows:

The valve d being open, and consequently the valve j shut, the water flows through pipe B into the body A, and passes up through the diaphragm a and stand pipe C, and is then drawn off through cock b .

The water, in its passage through the felt, has all the mud, dirt, and impure matters held in suspension, separated from it, the water passing upward, and the impurities or sediment falling to the lower end of the chamber.

When the flow of water is shut off by valve d , the hole k is opened, and all the accumulated sediment, &c., discharged through it.

Any water which does not pass back through the diaphragm when the hole k is opened, but remains on top, may be discharged through cock g .

We are aware that filters have heretofore been made in which the water could be made to flow through the filtering-medium in either one or the other direction, by setting or altering the mechanism or parts for that purpose, and therefore we do not claim such a device; but having thus described our invention,

What we claim, is—

1. A hydrant containing a filter; so constructed that the water shall flow through the filter when the hydrant is opened, and a portion of the water return through the filter and escape at another opening when the hydrant is closed, thereby making the apparatus self-cleaning, substantially as described.

2. The reservoir or vessel A, provided with the filtering-diaphragm A , in combination with the supply-pipe B, and the valves or cocks d and j , the latter being arranged to open and close alternately, substantially as described.

JOHN RAIBLE.
MATTHIAS REIS.
JOHANN RITTER.
